Primary Examiner — Karen S Acker*Assistant Examiner* — Wendy Arminio(74) Attorney, Agent, or Firm — Andrus Intellectual Property Law, LLP(57) CLAIM

The ornamental design for a garment with surface ornamentation, as shown and described.

DESCRIPTION

FIG. 1 is a front view of a garment with surface ornamentation according to my new design;

FIG. 2 is an enlarged top view thereof;

FIG. 3 is a side view thereof; and,

FIG. 4 is a rear view thereof.

The broken lines and the areas within the broken lines depict environment included to show the design in a position of use and form no part of the claimed design.
